UNITED STATES PATENT OFFICE.

HERBERT P. GREEN, OF KANSAS CITY, MISSOURI, ASSIGNOR OF ONE-HALF TO WILLIAM ARTHUR COLLINGS, OF KANSAS CITY, MISSOURI.

TATTING-SHUTTLE.

1,241,369.

Specification of Letters Patent. Patented Sept. 25, 1917.

Application filed April 19, 1916. Serial No. 92,115.

To all whom it may concern:

Be it known that I, HERBERT P. GREEN, a citizen of the United States, and a resident of Kansas City, in the county of Jackson 5 and State of Missouri, have invented certain new and useful Improvements in Tatting-Shuttles, and I do hereby declare that the following is a full, clear, and exact description of the same, reference being had 10 to the accompanying drawings, and to the numerals of reference marked thereon, which form a part of this specification.

Shuttles for tatting as heretofore constructed have usually consisted of a shank 15 or thread holder having side pieces rigidly fastened to the shank. These side pieces were tapered at both ends terminating in a point which was bent inwardly to contact the adjacent point of the opposite side member. This type of shuttle as commercially 20 manufactured has not proven satisfactory for the reason that the points nearly always required adjustment before one could use the shuttle for the reason that the pressure 25 between the points is very important in tatting. Another undesirable feature about the older type of unitary shuttles, is the excessive amount of time required to wind these shuttles with thread, such winding being a 30 particularly inconvenient operation since the thread must be held and drawn taut to pass between the points twice for each turn of the thread upon the shank. As a result the fingers of the operator are often cut by 35 the thread when the shuttle points are too tightly compressed, or if the points are too far apart the thread unwinds during tatting, or if the shuttle is accidentally dropped.

40 This invention relates to a tatting shuttle having removable side pieces and a removable spool adapted to greatly simplify and decrease the time of winding by hand, to permit replacement of a spool by another 45 containing thread of the same or different color, and to regulate the adjustment of the pressure between the shuttle points as desired.

It is an object therefore of this invention 50 to construct a tatting shuttle having a removable spool and sides to facilitate winding of the thread for use in the shuttle.

It is also an object of this invention to

construct an adjustable tatting shuttle adapted to be assembled or taken apart in a 55 minimum space of time.

It is also an object of this invention to construct a shuttle having a removable spool adapted to receive the sides slidably inter-fitted therewith to allow adjustment of the 60 shuttle points.

It is furthermore an object of this invention to construct a shuttle consisting of a removable spool arranged to permit the sides to be sprung into locking engagement there- 65 with.

It is finally an object of this invention to construct an adjustable removable spool shuttle simple in construction and inexpensive to manufacture. 70

The invention (in a preferred form) is illustrated in the drawings and hereinafter more fully described.

On the drawings:

Figure 1 is a top plan view of a shuttle em- 75 bodying the principles of my invention.

Fig. 2 is a side view thereof.

Fig. 3 is a section taken on line 3—3 of Fig. 1.

Fig. 4 is a section taken on line 4—4 of 80 Fig. 2.

Fig. 5 is a top plan view of the shuttle spool.

Fig. 6 is a view of the inner surface of the 85 side members.

Fig. 7 is a top plan view of a modified form of my device.

Fig. 8 is a side view thereof, showing the interfitting sides partly engaged in the spool.

As shown in the drawings:

The side members of the shuttle are designated by the reference numeral 1, and are curved and tapered toward both ends to afford points 2. Said side members are cut and bent inwardly at their central portions 95 to provide integral side extensions 3, and integral end extensions 4, leaving a longitudinal irregular opening in the side members, as clearly shown in Figs. 1 and 6, against and partly into which the fingers of 100 a person may be pressed to prevent the shuttle slipping from the hand during rapid work. The end portions of said inwardly bent extensions 4, are curved or bent to afford nubs 5, adapted to spring into locking 105 engagement with suitable apertures in the

end walls 6, of a removable unitary spool or thread holder denoted as a whole by the reference numeral 7.

To insure engagement of the side members with spool 7, the side extensions 3, extend through a central aperture in the spool and bear against the inner surfaces of side walls 8, of the spool. Said spool is flanged to afford flat integral end portions 9, and side portions 10, disposed at right angles to the respective walls 6 and 8. Said portions serve to retain the thread wound around the rectangular shaped drum formed by the walls 6 and 8, and further provide flat bearing or supporting surfaces for the inner surfaces of the shuttle side members 1. As shown in Fig. 3, small apertures are punched or stamped in the side walls 8, to permit one end of the thread to be passed therethrough and be tied around the spool 7. To facilitate the removal of the side members 1, from the spool 7, the side portions 10, are cut away as shown in Fig. 5, to allow a firm grasp to be had on said side members.

In the modified form of my device illustrated in Figs. 7 and 8, the reference numeral 11, denotes the side members of a shuttle which are curved inwardly and tapered to points at both ends. Rigidly secured in a longitudinal opening in each of said side members 11, by soldering or other suitable means, are frictional telescoping members 12 and 13, arranged to permit the member 12, to fit slidably into member 13. Removably mounted upon said member 13, is a shuttle spool comprising a rectangular hollow drum 14, adapted to receive said member 13, inserted therein, said drum 14, having rigidly soldered or secured on each end thereof flat end pieces 15, adapted to guide and hold the thread upon the spool and afford supporting or bearing surfaces for the side members 11, when the shuttle is assembled for use. Rigidly secured upon said drum 14, is a small pin 16, to afford a means of engagement for one end of the thread for winding. The end pieces 15, are cut away on both sides to facilitate gripping the sides 11, when it is desired to separate said side members to remove the spool.

The operation is as follows:

The operation is very simple and consists of first removing one or both of the side members 1, and then winding the thread upon the spool 7, after first securing the thread thereto by passing one end of the thread through the apertures in the side walls 8, and tying it around the spool. To assemble the shuttle for use it is only necessary to fit one of the nubs 5, of the side member 1, into the aperture in the end wall 6, and press inwardly on the side member, thus automatically springing the opposite nub 5, into locking engagement with the

aperture therefor in the opposite side wall 6. The other side member, may be attached to the spool in a similar manner, thus bringing the adjacent points 2, into contact with one another. This arrangement permits any number of spools to be used with the same shuttle side members. The end and side portions 9 and 10, may, of course, be omitted if desired, to permit thread cops already wound to be placed on the spool 7.

In the modified form of my device shown in Figs. 7 and 8, the spool may be wound with thread by catching one end of the thread around the pin 16, and then winding the thread around the drum 14. The spool is then engaged on the telescoping member 13, after which the telescoping member 12, is inserted into said member 13, and the side members 11, are pressed together to permit the adjacent shuttle points to contact, said members 12 and 13, frictionally engaging one another to hold the side members 11, together. It will, of course, be understood that the telescoping members may be square or circular in cross-section, and that the spool may be omitted entirely, in which case the thread may be wound directly upon the telescoping member 13, or thread cops already wound may be engaged on said member.

I am aware that various details of construction may be varied through a wide range without departing from the principles of this invention. I therefore do not purpose limiting the patent granted otherwise than necessitated by the prior art.

I claim as my invention:

1. In a device of the class described, an apertured rectangular spool, integral extensions thereon, tatting members, side and end extensions struck inwardly therefrom, nubs formed on said end extensions adapted to be sprung into locking engagement with the apertures in said spool, and said side extensions adapted to prevent lateral movement of said tatting members.

2. A tatting shuttle of the class described comprising a rectangular spool having apertures in the end walls thereof, and side members adapted to be lockingly sprung into engagement with said apertures.

3. In a tatting device of the class described a spool having apertures in the walls thereof, tapered side members, and nubbed extensions integrally formed on the inner surface of said members adapted to be sprung into locking engagement with said apertures.

4. In a device of the class described a spool comprising end and side walls having apertures therein, a plurality of integral extensions on each of said walls adapted for guiding and holding thread on said spool, curved shuttle side members, integral side

and end extensions on the inner face of said members, said end extensions adapted to be sprung into locking engagement with the apertures in said end walls, and said side extensions adapted to prevent said shuttle side members from lateral movement.

5. In a tatting device of the class described curved tapered sides, projections struck inwardly therefrom, and a spool having apertures in the walls thereof adapted to lock-

ingly receive said projection in said apertures to form a shuttle.

In testimony whereof I have hereunto subscribed my name in the presence of two subscribing witnesses.
